UNITED STATES PATENT OFFICE.

JOHN E. WOOTTEN, OF PHILADELPHIA, PENNSYLVANIA.

MOVING LOCOMOTIVE-ENGINES BY HAND-POWER.

Specification of Letters Patent No. 26,318, dated November 29, 1859.

To all whom it may concern:

Be it known that I, JOHN E. WOOTTEN, of Philadelphia, in the county of Philadelphia and State of Pennsylvania, have invented a new and useful Instrument for Moving Locomotive-Engines and Railroad-Cars for Short Distances upon the Track; and I do hereby declare that the following is a full, clear, and exact description of the construction and operation of the same, reference being had to the annexed drawings, making a part of this specification, in which—

Figure 1 is a perspective view of the instrument, Fig. 2, a vertical transverse section, Fig. 3, a vertical longitudinal section, and Fig. 4, a top view with the cap L removed, similar letters referring to similar parts.

It may be proper here to remark that the process of moving a locomotive engine or railroad car upon the track by hand is technically termed pinching and has heretofore been accomplished, chiefly by means of an ordinary crow bar.

The nature of my invention consists in providing a cylinder A, communicating by means of an opening B, with the pump barrel C, the cylinder A should be bored with accuracy and the piston D, nicely fitted to work within the same. The pump barrel C, should also be bored with accuracy and the plunger E, well fitted to work within it. The plunger E is actuated by means of arm F attached to shaft G, which is moved by the hand lever H. The mouth of the pump barrel C is slightly enlarged for the purpose of facilitating the entrance of the plunger E, when it may have been withdrawn for the purpose of replenishing the supply of fluid to the pump barrel C; this provision renders the use of valves unnecessary as will be hereinafter shown.

I, is a reservoir for containing a supply of oil, water, or other fluid which may be most convenient or desirable for the operation of the instrument.

L, is a cap covering the reservoir I to prevent the escape of the fluid.

Having thus fully described the construction of my improved instrument, which I have denominated a "Hydraulic propeller,"

I will proceed to explain its mode of operation which is as follows,

The cap L having been removed, oil, water, or other convenient or desirable fluid should be poured into the reservoir I, and in order that the pump barrel C may be filled at the same time, the plunger E should be withdrawn to the end of its stroke, when the entire cavity has been filled the cap L should be replaced and screwed down to a joint. The instrument being now ready for operation, should be placed upon the railroad track and the piston D brought to bear against the periphery of one of the wheels of the engine or car to be moved. The hand lever H should then be moved downward, when by means of its action the plunger E is forced into the pump barrel C, and the piston D is consequently driven against the wheel, which is urged forward and away from the instrument. By raising the hand lever H, the plunger E is withdrawn for the next stroke, when in consequence of the partial vacuum created by the back stroke of the plunger E; the pressure of the atmosphere causes the piston D to descend to the bottom of the cylinder A. The instrument should then be pushed forward as much as the engine or car has advanced, and the previously described operation should be renewed and carried on as often as occasion may render necessary.

If, in consequence of leakage around the plunger E, or piston D, the supply of fluid within the pump barrel C should be diminished; provision is made for replenishing the supply at the end of the back stroke of the plunger; as it is completely withdrawn from the pump barrel, thus affording ample means for entrance of the fluid from the reservoir I, into the pump barrel C, without the intervention of valves.

Having thus fully described the construction and operation of my improved hydraulic propeller, I do not claim the multiplication of power by means of the hydraulic pump, such being an old and well known device; but

What I do claim and desire to secure by Letters Patent is;

The application of the hydraulic piston D to the purpose of propelling a locomotive

engine or railroad car upon the track, by its direct action upon the periphery of the wheel as herein described, combined with the peculiar arrangement of the plunger E 5 in reference to the piston D whereby the latter is caused to advance and recede in concert with the plunger by the aid of atmos-

pheric pressure, and without the intervention of valves in the manner, and for the purpose substantially as herein set forth.

J. E. WOOTTON.
